UNITED STATES PATENT OFFICE.

HELGE A. BORRESEN, OF CHICAGO, ILLINOIS, ASSIGNOR OF ONE-HALF TO EDWARD R.
HILLS, OF CHICAGO, ILLINOIS.

WATCH BARREL.

Original application filed July 10, 1916, Serial No. 108,290. Divided and this application filed April 29, 1920. Serial No. 377,598.

My invention relates to watches and more particularly to main springs and the means for attaching the same to the winding arbor of a watch.

5 The present application is a division of
application Serial No. 108,290, filed July 10,
1916, allowed Oct. 10, 1919.

One of the principal objects of my invention
10 consists in the provision of means for
attaching the end of a main spring to the
winding arbor in a detachable manner, and
so constructing the winding arbor and main
spring co-operating therewith as to automatically
15 guide the main spring into position about said arbor. More particularly, it
is an object of the invention to provide improved
means for attaching the inner extremity of main springs to winding arbors
in a secure manner, and at the same time
20 enable the main spring to be automatically
forced home.

Other objects and advantages of the invention will occur in the description of the invention and the accompanying drawings showing various forms that my invention may take and in which

Fig. 1 is a transverse sectional view of a winding barrel structure of a watch, showing the winding ratchet in the lower movement plate and a main spring with the improved means for attaching the same to the winding arbor:

Fig. 2 is a sectional view thereof illustrating the attaching means for the spring; Fig. 3 is a detail perspective view of the inner extremity of the main spring coil.

Fig. 4 is a fragmentary sectional view of a winding arbor and associated parts, showing a modified anchorage for the spring:

40 Fig. 5 is a fragmentary plan view of the end of the spring used with the winding arbor shown in Fig. 4;

Fig. 7 is a fragmentary plan view of the
45 end of a main spring with a further modified

Fig. 8 is a sectional view of the form of

Fig. 8 is a sectional view of the form of spring shown in Fig. 7 associated with a modified form of winding arbor;

Fig. 9 is a fragmentary sectional view of 50 a winding barrel structure showing the winding arbor and a main spring with a further modified form of attaching means associated therewith;

Fig. 10 is a fragmentary perspective view 55 of the inner end portion of said spring, and

Fig. 11 is a plan view illustrating the engagement of this form of main spring with the winding arbor, shown in Fig. 9.

Referring particularly to Figs. 1 to 3 inclusive, I show a form of the invention as applied to a watch model in which the winding ratchet 12 is mounted in the lower movement plate 13. The lower movement plate 13 carries the bridge plate 14 which has

an annular sleeve 15. The winding ratchet 12 with its extending hub 16 is mounted on this sleeve 15 and is rotatable thereon. The winding ratchet is confined in the space between the movement plate 13 and the bridge 70

14. The main arbor 17 carries the spring barrel 18 and is mounted in suitable bearings fixedly carried as illustrated. The main arbor 17 is tapered as shown and is provided with a circumferentially grooved portion 19 75

which thus transforms this arbor into a structure having maximum bearing supports as far apart as possible and permitting an accurate aligning drive fit. Fig. 1 to 3 demonstrate the practicability of mounting the 80

demonstrate the practicability of mounting the winding mechanism in the lower plate, yet removing the barrel and main wheel upwardly through the upper movement plate 20 by

simply removing the bridge 21. In order to automatically guide home the main arbor 17 into its bearings the sloping shouldered recess 22 is provided. 85

The winding arbor hub 16 is beveled as shown at 23 so that the spring may be automatically forced home. In order further to procure an automatic meeting of the parts

I have beveled the inner extremity 24 of the main spring 25 as shown more clearly in Fig. 3. Hooks provided on the inner coil of the main spring to be used in combination with the old type barrel with a stationary arbor need not possess the automatic assembling principles as herein provided as

the assembling of these various parts is performed before the barrel is introduced into the watch movement, while in my type of construction the assembling of these parts 5 must be automatically accomplished as the barrel is introduced into the movement, and as shown in the drawing several forms of substantially automatic connections have been devised to make my combination practical and easily manipulated. The main spring extremity is bent as shown at 26 in order to cooperate with a lip 27 provided upon the hub 16. Thus the main spring barrel together with the main spring are 15 moved in a position telescopingly around the hub 16 and then a rotation of the winding ratchet 12 causes the eventual engagement of the tongue 24 by the lip 27 as is apparent from Fig. 2. In order further to 20 guide the winding ratchet 12 I provide an annular rim 28 as shown in Fig. 1 which more accurately confines this winding ratchet in position.

In Figs. 4, 5 and 6 I show a modified 25 form of the structure shown in Figs. 1 to 3 in that the main spring 29 has a cup-shaped projection 30 formed thereon which properly aligns and engages the corresponding recess shown at 31 in the winding arbor 32 in Fig. 4, thus seating and maintaining the parts 30 and 31 in alignment.

In Figs. 7 and 8 I show a further modification in which the main spring 32 has a punched V-shaped straight tongue 33 engaging in a suitable recess in the annular arbor 34.

Referring more particularly to Figs. 9, 10 and 11 I show a structure in which the lower movement plate 13' accommodates the bearing for the main arbor 17'. The winding ratchet 12' is provided with a winding arbor 16' beveled at 23'. The improved structure for engaging the inner extremity of the main spring 35 includes the provision 45 at the extremity thereof of a cylindrical section 36' beveled as shown at 37. This beveled portion readily slides on the beveled portion 23' of the hub 16'. The hub 16' is provided with a circular recessed portion 38 to accommodate this rounded extremity of 50 the main spring. The main spring extremity in order to cooperate properly with the annular projection 39 which acts as a stop to keep the spring out of the path of arbor 55 16' has a portion of the cylindrical extremity 36 cut away as shown in Figs. 9 and 10 so that the cylindrical portion may move inwardly over the projection 39, said projection, however, still maintaining the 60 inner convolutions of the spring out of the path of the arbor 16'.

The assembly of the device is accomplished as follows: The beveled end portion of the winding arbor engages with the beveled edge 24 or 37 of the spring to force

the same outwardly as the barrel containing the spring is moved down on said arbor. After the spring has been seated the beveled end will, of course, rest against the beveled shoulder shown in Figs. 1 to 9. But it is 75 the beveled end of the winding arbor that causes the spring to be spread so as to allow the winding arbor to be passed through the middle thereof. It will be seen that the end of the spring that is beveled, that is the hook 26 or the loop at 36 extends inwardly beyond the innermost coil of the spring. Accordingly this is the part that will first engage with the winding arbor, both the ends of the winding arbor and the edge portion of the spring being beveled at the end thereof, the two parts when moved relatively to each other will act as wedging surfaces to force the spring outwardly so as to enlarge the inner coil thereof to such an extent that it will be greater in diameter than the largest part of the winding arbor; thus making it easier to pass the spring over the winding arbor. Then by turning the barrel or the spring therein about the winding arbor the hook or other fastening device will engage in the recess in the winding arbor.

From what has been described it will be clear that my invention is capable of many and various modifications.

Having thus described certain forms which my invention may take, what I claim as new and desire to secure by Letters Patent is:

1. In a timepiece of the type having the main wheel, main spring barrel and main arbor assembled and rotating together, an annular winding arbor having a beveled extremity and a main spring correspondingly beveled to automatically assemble the same about said winding arbor, said barrel having a hub projecting into the inner coil of the main spring to maintain the same extended in such a position that the corresponding bevels of the main spring and arbor will cooperate to automatically assemble the same about said winding arbor.

2. A watch having a winding arbor, a main spring barrel having a projecting hub and a main spring, said winding arbor having its extremity beveled to guide the main spring into position about said arbor when the parts are being assembled, said main spring having its inner extremity beveled to cooperate with the beveled portion of said arbor, said main spring having a hooked extremity to secure the main spring in position, said hub extending into the inner coil of said spring to hold the same in distended position so as to be readily engaged by the beveled portion of said winding arbor.

3. In a watch, a winding arbor, a main spring barrel and a main spring, said winding arbor having a beveled end portion, and a recess having an inclined wall portion,

said main spring having an integral hook on the inner end thereof provided with a beveled edge adapted to engage with the beveled end portion of said arbor to guide engagement of said beveled portions, said hook riding down said inclined surface into engagement with a hook receiving formation in said recess. ¹⁰

⁵ said spring in position around said barrel, means on said barrel for holding the inner coil of said spring distended for automatic

In witness whereof, I hereunto subscribe my name this 23rd day of April, A. D., 1920.

HELGE A. BORRESEN.
